UNITED STATES PATENT OFFICE.

PATRICK J. LYONS, OF PHILADELPHIA, PENNSYLVANIA.

RAILWAY-TRACK CONSTRUCTION.

1,249,147.

Specification of Letters Patent. Patented Dec. 4, 1917.

Application filed August 14, 1917. Serial No. 186,094.

To all whom it may concern:

Be it known that I, PATRICK J. LYONS, a citizen of the United States, residing at Philadelphia, county of Philadelphia, and 5 State of Pennsylvania, have invented a new and useful Improvement in Railway-Track Constructions, of which the following is a full, clear, and exact description, reference being had to the accompanying drawings, 10 which form a part of this specification.

My invention relates to a railway track construction for use in crossings, switches, frogs, mates, etc., etc., on either steam or street railway lines, of such a character as 15 to permit of the ready removal and replacement of the parts receiving the greatest wear without interfering with or damaging other parts.

In a crossing, for example, the point 20 where the wheel flangeways meet is subject to greater wear than any other part of the track, due to the jumping of the wheel over the intersecting flangeway. It is customary to place a removable plate or center 25 in the track at this point, in order to permit of renewal of the worn portion without the necessity of renewing the entire crossing. The devices for this purpose now in use are found to have many defects, 30 principally that they are very difficult to remove and that their removal frequently results in irreparable damage to the entire crossing. The object of my invention is to provide a track construction having a re- 35 movable center adapted for use in crossings, switches, etc., etc., which may be made up in any shape and used at any angle, which will be positively held in position when placed and at the same time may be 40 readily removed without possibility of damage to any other parts and with a minimum of time and labor.

It is also customary in the known constructions to bind the center and in some 45 cases maintain it in place with soft metal, poured in after the center is placed in the crossing. This operation is expensive, due to the high price and excessive requirements in the amount of metal used and renders the 50 center difficult to remove.

A further object of my invention is to provide a track construction wherein the use of soft metal is greatly reduced and in no way hinders the removal of the center.

Referring to the accompanying drawings, 55 in which I have illustrated my invention, together with a modification thereof:

Figure 1 is a plan view of a section of a crossing.

Fig. 2 is a cross section on line 2—2, 60 Fig. 1.

Fig. 3 is a face view looking in a diagonal direction toward the lower right hand corner of Fig. 1.

Fig. 4 is a perspective view of a removable center. 65

Fig. 5 is a plan view of the retaining key or pin.

Fig. 6 is a side view of the tool adapted 70 to draw the retaining key.

Fig. 7 is a plan view of crossing showing a modification of the structure of Fig. 1.

Fig. 8 is a cross section through line 8—8, 75 Fig. 7.

Fig. 9 is a perspective view of a removable center of modified construction. 75

Fig. 10 is a transverse cross section of Fig. 7.

Referring more particularly to Figs. 1—6, the rail sections *a* are each held at one of 80 their ends in the casting *b*, their other ends being connected in any suitable manner to the line of track, not shown. The casting, having flange grooves *k* alining with the grooves in the trackway, is provided with 85 the chambers *c* and *d* for the reception of the inset or center *e* and its depending portion *f*. The center *e* has its corners cut off as at *e'*. At one of the corners of the casting between the rail sections the vertical 90 slot *g* is cut out and extends the depth of the casting. Spaced from the top of the casting and opening into the slot *g*, the keyway *h* extends on a horizontal plane diagonally into the casting, passing through the 95 chamber *d*. The sides of the slot *g* near their outer edge are provided with vertical slots *i* which extend downwardly to a point below the bottom of the keyway *h*, and provide guides for the wedge *j* which is provided on one side with the lug *p*. 100

The inset or center *e*, adapted to fit into the chamber *c*, is provided on its surface with wheel flange grooves *l*, adapted to aline with the grooves *k* in the casting, the 105 depending portion *f* of the inset, adapted to fit into the chamber *d*, is provided with the opening *m* adapted when the center is in

place, to aline with the horizontal keyway h in the casting.

The key or pin n , provided near one end with the elongated slot o , is adapted to extend into the keyway h , through the opening m in the depending portion of the center.

The tool q , provided with the handle r , is of V-shape and is adapted to enter the slot o in the key n , and draw it out of the keyway h , as partially indicated in broken lines, Fig. 2.

Referring to Figs. 7-10, which illustrate a modification of my invention adapted to a crossing: The casting s is provided with wheel flange grooves t and the recessed chamber u the bottom of the chamber having the upwardly extending eyes v . The casting is provided at both ends with the vertical slots g' , having slots i' in their sides, providing guides for wedges j' which are provided with lugs p' , similar to the slots g and i and wedge j , Fig. 3, and the horizontal keyways h' extending between the chamber u and the vertical slots g' .

The inset or center y having wheel flange grooves adapted to aline with the grooves t is provided with openings z extending into its body from both ends and slots z in its bottom for the reception of the eyes v in the bottom of the chamber u . The keys n' provided with the elongated slots, o' are similar in construction to the key n , Fig. 5.

Referring again to Figs. 1-6, in practice the manipulation of my device is as follows:

The chambers c and d in the casting are cleaned out and the inset or center e set in flush with the upper surface of the casting, and so that the opening m in its depending portion f is alined with the keyway h . The slot o in the key n is filled with clay or other heat resisting substance and clay is passed into the vertical slot g . The key is then passed into the keyway h , solid end first, leaving a portion of the slotted end protruding into the vertical slot g . The wedge j is inserted in the guide slots i and driven down to maintain the key in position. Babbitt metal is then poured into the casting through one of the apertures e' , the remaining apertures being plugged with clay, the metal passes into the chambers c and d , filling any interstices between the center and casting, forms a bed for the center by filling underneath it, and fills in about the key in the opening m and keyway n . No metal, however, gets into the slot in the key n or in the vertical slot g , being kept out by the clay filling. The metal makes the casting, center and key solid and forms a bond for the passage of electricity through the rails.

Upon the cooling of the metal, the crossing is ready for use, being held solidly in place by the key and filling metal.

When it is desired to remove the center, the wedge j is driven out by a hammer tap on the lug p , the point of the tool q is inserted in the slot g and driven down until it drives the clay out of the slot o in the key, the point then enters the slot o and, as the tool is driven farther down, it tends, due to its shape, to draw the key out of the keyway. As soon as the key is started it may be readily drawn out and the center removed in the usual manner. When the center is put in, only sufficient metal is used to form a bed and to seat the center in solidly to prevent it from working and to prevent the entrance of water and dirt which, in time, would get under the center and tend to raise it. The amount of soft metal used is greatly less than in the present constructions, as it is only used to solidly connect the center and key with the casting. Since the metal is positively prevented from entering the slot g and the slot o in the key no metal need be cut out preparatory to removing the center, which renders its removal easy and is saving of time and labor.

The operation of the modifications shown in Figs. 7-10 is similar to that above described and it is thought will be readily understood.

I do not wish to limit my invention to the modifications shown, as it is equally adaptable to any other type of track construction, where a removable part is used because of excessive wear or for any other reason.

Having now fully described my invention, what I claim and desire to protect by Letters Patent is—

1. A track construction comprising a casting, an inset inserted in a recess in the casting, a key inserted through alining keyways in the casting and inset and provided with a longitudinally extending slot, said casting being cut away from its upper face to said keyway, said cut away portion extending from in front of the rear of the slot to a point back of the solid part of the key at the rear of the slot, and a holding pin extending downward through said cut away part of the casting and engaging the solid part of the key back of the rear of the slot.

2. A track construction comprising a casting, an inset inserted in a recess in the casting, there being a horizontal keyway partly integral with the casting and partly integral with the inset, part of the keyway between its ends being integral with the inset, a key inserted in the keyway, and a downwardly extending pin engaging said key and holding it from withdrawal.

3. A track construction comprising a casting, an inset inserted in a recess in the casting, there being a horizontal keyway partly integral with the casting and partly

integral with the inset, part of the keyway between its ends being integral with the inset, a slotted key inserted in said keyway, said casting being cut away from its upper 5 face to said keyway, said cut away portion extending from in front of the rear of the slot to a point back of the solid part of the key at the rear of the slot, and a holding pin extending downward through said cut 10 away part of the casting and engaging the solid part of the key back of the rear of the slot.

4. A track construction comprising a casting having a recess, a keyway extending upward from the bottom of said recess, an inset inserted in said recess, said inset having 15 an opening for the reception of said keyway

and having a keyway alining therewith, and a key extending through both keyways.

5. A track construction, comprising a 20 base, cut out for the reception of an inset, having a vertical slot in its periphery and a keyway extending from said slot into said cut out portion, eyes extending upwardly from the bottom of said cut out portion, an 25 inset having a horizontal opening and openings for the reception of said eyes, adapted to set in the base, and a slotted pin adapted to pass through said keyway into said inset and through said eyes. 30

In testimony of which invention, I have hereunto set my hand, at Philadelphia, on this 9th day of August, 1917.

PATRICK J. LYONS.
